UNITED STATES PATENT OFFICE.

WALTER P. EVANS, OF MEADOW GROVE, NEBRASKA, ASSIGNOR OF ONE-HALF TO JESSE O. CARTER, OF MEADOW GROVE, NEBRASKA.

PAPER-HANGING MACHINE.

No. 914,254.

Specification of Letters Patent. Patented March 2, 1909.

Application filed May 7, 1908. Serial No. 431,401.

To all whom it may concern:

Be it known that I, WALTER P. EVANS, a citizen of the United States, residing at Meadow Grove, in the county of Madison and State of Nebraska, have invented certain new and useful Improvements in Paper-Hanging Machines; and I do declare the following to be a full, clear, and exact description of the invention, such as will enable others skilled in the art to which it appertains to make and use the same.

My invention relates to wall papering or bill posting machines.

The object of the invention is to provide a machine upon which the wall paper or bills to be posted are held, pasted and distributed as the machine is moved over the surface which it is desired to cover.

In wall papering it is necessary for the operator to unroll the paper from the roll, paste it, fold it and smooth it upon the wall.

It is the object of my invention to obviate these unnecessary steps and broadly speaking consists in supplying paper from the roll to a pasting device, and conveying it to a smoothing roller which applies it to the surface to be covered. In bill posting these features are important because it requires as the usual rule, one man to paste and the other to post the bills where rapidity is the object.

A further object of the invention is to provide means whereby the paper from the roll may be severed at the proper time so as to disconnect the part pasted upon the wall or board from the remainder of the roll. This severing is not complete but only partial so that a further supply may be started under the smoothing roller before the part just pasted is entirely disconnected.

With these and other objects in view, the invention consists of certain novel features of construction, combination and arrangement of parts, as will be more fully described and particularly pointed out in the appended claims.

In the accompanying drawings, Figure 1 is a front elevation, Fig. 2 is a side elevation, Fig. 3 is a bottom plan view, Fig. 4 is a central vertical sectional view.

Referring more especially to the drawings, 1 and 2 represent side plates in which the several rolls are mounted, and upon which the pasting mechanism is supported. These side members have extending upwardly from

their rear ends handle supporting bars 3, which are connected to the triangular members 4, between which the handle 5, is secured. The supporting bars 3 are apertured to receive the transverse paper roller shaft 6, which is arranged directly below the pasting tank 7, which is carried by the side members. The end pieces 8, of the side members are extended up above the tank 7, where they are provided with journal bearings to receive the pasting roller 9, over which the paper 10, from the roller shaft 6 passes.

In order to hold the paper in proper position over the pasting roller I provide a pair of diagonally extending arms 11, pivotally connected to the side pieces 1 and 2, provided with journal bearings to support the stub shafts of a pressure or guide roller 12, under which the paper 10 passes to be taken up by the feeding rollers 13 and 14. The feeding roller 13 is provided with a plurality of collars throughout its length, which prevent the entire surface of the pasted side of the paper from engaging the roller, and the roller 14 is provided with a felted surface 15. These feeding rollers are driven by suitable pulleys 16 and 17, carried upon the outer ends of their shafts and belted to a pulley 18, carried upon the outer end of the shaft 19, of the smoothing roller 20, by a belt 21, which after passing over the pulleys 17, 18, is conducted to a pulley 22, carried upon the end of the shaft of the pasting roller 9. The paper passes over the pasting roller beneath the pressure roller 12 between the feed rollers 13 and 14, between the jaws 23 and 24, of the severing mechanism to the smoothing roller where it is pasted upon the wall, or surface to be covered. The jaw 23 comprises a cylindrically slotted member extending between the side pieces 1 and 2 with its slot arranged in such a position as to be engaged by the toothed edge of the jaw 24. This latter jaw is provided with journal pins, one of which is extended out to form the operating lever 25, which is connected with a hand lever 26, by a flexible link 27. The jaw is normally held in open position by a spring 28, which is carried by the side member 1. The serrated edge of the knife only perforates or partially severs the paper so that a complete disconnection from the main roller is not made until after a substantial part of the next strip to be pasted is underneath the pressure roller.

The upper part of the paste tank 7 is slot-

ted as at 29, so as to be covered by the pasting roller and a shield 30, to prevent the paste from contacting with the paper except when forced into engagement with the pasting 5 roller by the pressure roller 12. A suitable capped opening is made in the tank so that it may be filled at any time.

In order that the paper may be trimmed after it is placed in the pasting machine, instead of causing it to be cut by a separate operation, I secure a cutting disk 13^a, to the end of the roller 13, and a similar disk 15^a, to the roller 14, which latter disk is overlapped by the former. As the paper passes between the two the margin thereon is separated from the body of the sheet.

From the foregoing description, taken in connection with the accompanying drawings, the construction, and operation of the invention will be readily understood without requiring a more extended explanation.

Various changes in the form, proportion and the minor details of construction may be resorted to without departing from the principle or sacrificing any of the advantages of this invention as defined in the appended claims.

Having thus described my invention what I claim and desire to secure by Letters Patent is:—

1. In a device of the class described, a frame, an applying roller journaled therein, a pair of feeding rollers driven by said applying

roller, a paste tank, a paste roller adapted to feed paste to the paper from the tank, a pivoted guide roller arranged between the feed rollers and paste roller, a severing device arranged between the feed and applying rollers, and means controlled by the operator for operating the severing device.

2. In a device of the class described, a frame, an applying roller journaled therein, a pair of feeding rollers driven by said applying roller, a handle connected to the frame for manipulating the device, a paste tank having a discharge end directed toward the handle and a discharge opening directed transversely to the handle, a paste roller journaled in the frame and adapted to close the opening, arms pivoted to each side of the tank, a guide roller journaled in said arms between the paste roller and the feeding rollers, a shaft journaled in the frame, a knife secured to said shaft, a lever under control of the operator for operating the knife, and a slotted cylinder arranged between the feeding and applying rollers adapted to support the paper to receive the edge of the knife.

In testimony whereof I have hereunto set my hand in presence of two subscribing witnesses.

WALTER P. EVANS.
